UNITED STATES PATENT OFFICE

2,668,495

PENCIL MARKING MACHINE

Gregory G. Wright, Cincinnati, Ohio, assignor to
 Pencil Crafts, Inc., Georgetown, Ky., a corporation of Kentucky

Application November 7, 1950, Serial No. 194,409

6 Claims. (Cl. 101—110)

1

This invention relates to a pencil marking machine of the type in which a name or other legend is impressed upon a pencil in gold leaf or the like.

It is a general object of the invention to provide a machine of the class above set forth which will be relatively simple in operation but which will nevertheless make perfect markings on pencils and make these markings on a succession of pencils rapidly.

It is another object of the invention to provide a novel locking arrangement for the printing wheels whereby it is possible to make the individual letters larger than has been possible heretofore.

It is yet another object of the invention to provide a clearing arrangement for clearing the letters set up on the printing wheels prior to setting up a different legend.

Still another object of the invention resides in the provision of a double feed-dog for simultaneously feeding a marked pencil away from marking position to a delivery point while at the same time feeding an unmarked pencil into marking position.

Another object of the invention resides in the provision of an adjustment whereby the pressure of the printing stroke may be varied.

These and other objects of the invention which will be set forth in more detail hereinafter, or which will become apparent to one skilled in the art upon reading these specifications, I accomplish by that certain construction and arrangement of parts of which I shall now disclose an exemplary embodiment.

Reference is made to the drawings forming a part hereof and in which—

Figure 1 is a front elevation of the machine showing interior parts in broken lines.

Figure 2 is a fragmentary cross sectional view taken on the line 2—2 of Figure 1 on an enlarged scale.

Figure 3 is an enlarged perspective view of one of the agitating fingers.

Figure 4 is a cross sectional view looking downward, taken on the line 4—4 of Figure 9.

Figure 5 is a vertical cross sectional view through the machine taken on the line 5—5 of Figure 1 or Figure 7.

Figure 6 is a detailed perspective view of one of the connecting link members seen approximately in the middle of Figure 5.

Figure 7 is a vertical cross sectional view taken on the line 7—7 of Figure 5.

Figure 8 is an enlarged perspective view of one of the hold-down members.

2

Figure 9 is a vertical cross sectional view taken on the line 9—9 of Figures 1 and 7.

Figure 10 is a diagram showing the arrangement of the printing wheels to show how the locking notches are provided.

Figure 11 is a plan view of the pencil feed member and is a plan view of Figure 12.

Figure 12 is a front elevational view of Figure 11.

Figure 13 is an end elevation of Figure 12, as seen from the left.

Figure 14 is a cross sectional view taken on the line 14—14 of Figure 12 on an enlarged scale.

Figure 15 is a fragmentary front elevational view of a portion of Figure 12 in a different position, and

Figure 16 is a cross sectional view taken on the line 16—16 of Figure 15 on an enlarged scale.

Generally speaking, the machine rests upon a base 10 on which is mounted the framework 11 and the machine is enclosed in a housing 12. A bracket 13, which may be a part of the framework 11 or suitably secured thereto as at 14 by screws, is provided with a bearing boss 15 in which are mounted ball bearings 16, journaling the main crankshaft 17. Secured thereto, as by the set screw 18, is a pulley 19, having a manually actuatable portion 20 extending outwardly through a circular aperture 21 in the front of the casing. The pulley 19 is driven through a belt 22 by an electric motor 23. The motor 23 is mounted on a bracket 24 which is secured as at 25 to an extension of the bracket 13. In this way the distance between the pulley 19 and the motor may be adjusted. In order to support the motor for shipment there may be provided the hole in a boss 28 of the base.

By manual rotation of the pulley 19, by means of the portion 20, or by operation of the motor 23 the crankshaft 17 is rotated.

The crankshaft 17 has the crankarm 29 upon which is pivotally mounted a lever 30. Preferably a ball bearing 31 is provided at the journal. A link 32 is pivoted to the lower end of the lever 30 at 33 and is pivotally mounted at 34 eccentrically of a worm wheel 35. A worm 36 on the shaft 37 is mounted in a bracket 38 and is provided with a knurled knob 39 by means of which the worm wheel 35 may be rotated so as to adjust the pivot point 34 for a purpose which will be described more in detail hereinafter. After the position of the pivot point 34 has been adjusted, the link 32 may pivot about the pivot 34 which then will remain fixed.

A link 40 is pivoted at 41 to the upper end of

the lever 30 and is connected at 42 to the pencil feeding mechanism which will be described in more detail hereinafter. It will be apparent that as the crankshaft 17 rotates, the central pivot point 43 of the lever 30 will travel in a circular path about the axis of the crank 17. Because of the fact that the lower end is connected by the link 32 to a fixed pivot, the lever 30 will be constrained to oscillate back and forth, and this oscillatory movement is transmitted by the link 40 to the pencil feeding mechanism.

A shaft 44 is mounted in the frame 11 in a position at right angles to the crankshaft 17 and the shaft 44 is caused to oscillate by means of the mechanism now to be described.

A twisted link 45 is pivoted at 46 intermediate the length of the links 32. At its other end the link 45 is pivoted in a fork 47 of a lever 48. The lever 48 passes through and is pinned by the pin 49 to the shaft 44 (see Figures 5 and 6). From the foregoing it will be clear that as the lever 32 oscillates under the influence of the crankshaft 17, the twisted link 45 will be caused to move up and down, and through the connection with the pin 48 will cause the shaft 44 to oscillate.

The shaft 44 carries the eccentric portion 50 on which the U-shaped pencil carriage 51 is journaled. The pencil carriage and its associated parts are best seen in Figures 11 to 16 inclusive, and they will be described in more detail hereinafter. For the present however, it will be understood that at each revolution of the crankshaft 17 the pencil carriage 51 will be caused to move up and down so as to carry out a printing operation.

In connection with the printing of the pencils a material such as commercial gold leaf is used, and I have provided feeding means for the gold leaf which operate from the same crankshaft 17. A roll support having a flange 52 is bolted or otherwise suitably secured to the frame as at 53 (Figure 4). The roll of gold leaf which is indicated at 54 is supported on a pin 55 extending from the flange 52. The roll 54 is mounted upon a cylinder 56 having a flange 57 and the detent fingers 58 which engage in apertures 59 to lock the gold leaf roll in position. From the roll 54 the gold leaf ribbon passes over the pencil carriage which will be described in more detail hereinafter to the feeding means. The feeding means comprises a toothed or notched roller 60 (Figures 4, 5 and 9) and a pressure roller 61 pressing the ribbon against the feeding roller 60. The roller 60 is mounted upon a portion of the frame 11 and the roller 61 is mounted upon a lever 63 pivoted as at 64 on the casing of the machine. A spring 65 urges the lever 63 in a counter-clockwise direction so that the roller 61 bears against the gold leaf ribbon.

Rotation of the feeding wheel 60 is accomplished as follows. A link 66 is pivoted to the shaft 67 of the feed wheel 60 and at its other end at 68 the link 66 is pivoted to another link 69. The link 69 in turn is pivoted to a block 70 secured to an extension of the pin 48. Thus as the crankshaft rotates and the pin 48 is rocked the link 66 will likewise be rocked about the axis 67 of the wheel 60.

A feed pawl 71 is pivoted to the link 66, and with each oscillation of the arm or link 66 the pawl 71 causes the wheel 60 to advance one step in a counter-clockwise direction as seen in Figure 5. The wheel 60 is prevented from return-

ing by the action of a second pawl 72 having a bellcrank 73 to which is secured the tension spring 74. In this way for each rotation of the crankshaft 17 the toothed wheel 60 is given a partial revolution, thereby to advance the gold leaf ribbon one step to insure that a fresh surface of ribbon is used.

The links 62 are pivoted on the shaft of the roller 60 at their one ends, and at their other ends they are pivoted to the member 51 to guide it during its up and down movements.

Returning now to the pencil carriage, particularly to Figures 11 to 16 inclusive, the mounting of the carriage 51 has already been described.

15 It consists of two complementary halves which are held together by the bolts 80. Channels are cut in the two halves of the member 51 to provide the passages 81 and 82 with the connecting passage 83 for the pencil feeding mechanism. 20 At its upper end the member 51 is provided with the surfaces 84 which are arranged to accommodate the standard hexagonal pencil. The pencil is indicated at 85. In order to insure that the pencil 85 which is to be marked is held in proper position against the surfaces 84 the hold-down members 86 are provided. These are secured to the member 51 and are provided with the spring fingers 87 to bear against the upper side of a pencil to hold it in proper position. Lips 30 85a are provided to serve as guides for the foil ribbon to prevent tearing of the ribbon during its feeding movement. From a consideration of Figures 11 and 12 it will be observed that the pencil trough constituted by the surfaces 84 is 35 more than long enough to accommodate two pencils end to end. Thus the pencil 85 is shown in position to be printed upon, while the pencil 85a has just entered the trough from the feeding hopper and will be the next pencil to be marked.

40 The pencil feeding mechanism consists essentially of two bars 90 and 91 which are linked together at their ends by the links 92 and 93, the ends of the links 92 and 93 extending above the member 90 to constitute the feed dogs 94 and 95. 45 The link 40 mentioned above is connected to the links 91 and 93 as at 96. The bar 90 rides in the guideway 81 while the bar 91 rides in the passage 82. The passage 82 is somewhat larger to permit relative movement between the bars 90 and 91. 50 The linkage between the bars 90 and 91 and the links 92 and 93 being a free linkage, it will be clear that when the link 40 is moved toward the left, the parts will assume the condition shown in Figure 15 and the dogs 94 and 95 will be in their raised position. When the link 40 moves toward the right, as shown in Figure 12, the bar 91 will be moved toward the right with respect to the bar 90 and the dogs 94 and 95 will assume the position shown in Figure 12. In the position of Figure 12 the dogs 94 and 95 clear the lower sides of the pencils, but on the return stroke toward the left of the link 40 the dogs 94 and 95 will be raised so that the dog 94 will move the pencil 85 from marking position to discharge it from the machine, while the dog 95 will engage the pencil 85a to move it into marking position.

55 It will be clear from the foregoing that for each revolution of the crankshaft 17 a pencil in the marking position will be discharged and another pencil will be moved into marking position. Agitator fingers 100 are secured to the pencil trough and their function will be described hereinafter.

70 The hopper for pencils to be marked is disclosed above the right hand end of the pencil carriage shown in Figures 11 and 12. It is seen

in cross section in Figure 2. The bottom of the magazine between the plates 104 is open to provide room for the passage of the agitator fingers 100 mentioned above. Since the entire pencil carriage moves up and down at each stroke of the machine it will be clear that the agitator fingers 100 extending up into the pencil hopper move the pencils and assist in lining them up so that they can pass down between the agitator fingers 100 onto the surfaces 84 of the pencil carriage. The printing wheels are mounted on the upstanding members 105 extending above the main casing. The individual printing wheels indicated at 106 are mounted upon a sleeve 107 which is mounted in the members 105 and in which there is provided a suitable heating element 108. Each printing wheel 106 is provided with a manually operable tab 110 by means of which the proper characters may be aligned for printing. Means are also provided for locking the printing wheels in any desired set position so that they will not be accidentally displaced during the operation of the machine. To this end I have provided a novel arrangement of the individual printing wheels as best seen diagrammatically in Figure 10. Each printing wheel is divided into three portions of 120° arc each. One-third of the printing wheel comprises the visible indicia by means of which the desired character is set up; another third comprises the printing characters corresponding to the visible indicia and with which the actual impression is made on the pencil; and the other third is provided with a number of locking notches, one for each printing character, plus one for a zero position. The printing characters can thus be larger than has been possible heretofore because it has been customary to provide locking notches between the printing characters. By the arrangement described above wherein the locking notches are divorced from the printing characters the characters themselves can be larger in dimension without interfering with proper locking of the printing wheels. An index bar is provided at 111 and in order to set up a desired name the appropriate fingers 110 are operated to bring the characters desired opposite the index bar 111. When they are opposite the desired characters, then those desired characters will be properly aligned on the printing character portion of the wheels in a position to print on the pencil 85. Mounted on the sleeve 107 to each side of the group of printing characters are the lever arms 112, between which extends the rod 113. A member 114 is mounted on the rod 113 so that it may be slid back and forth along the member 113 as desired and so that it may be tilted one way or the other as desired. The member 114 can be used to clear the printing characters by tilting it to the position shown in broken lines in Figure 9. If the member 114 is moved to the broken line position of Figure 9 and then the entire unit comprising the arms 112, the rod 113 and the member 114 are pushed toward the rear of the machine or in a clockwise direction as seen in Figure 9, the inwardly extending portion of the member 114 will engage the tabs 110 and move them toward the rear of the machine. The member 114 is of a length to move only a limited number of the tabs 110 so that the effect required to clear the machine is not so great. A number of keys may be cleared and then the assembly may be swung forward, the member 114 moved over and again pushed to the rear whereupon a second group of tabs will be moved to clear position.

The levers 112 also actuate the locking mechanism which will now be described. A lever 115 is pivoted as at 116 in the casing and has at its opposite end a locking tooth 117. The locking tooth 117 extends across all the printing wheels and at its other end is secured similarly to a second lever 115 exactly similar to the one just mentioned. Intermediate their lengths the levers 115 are pivoted to links 118 which in turn are pivoted to links 119 which are pivoted to the hubs 120 of the levers 112. A spring 121 is connected at one end to the pivot point between the links 118 and 119 and at its other end is secured to the casing of the machine. The link 119 also is provided with a lug 119a which abuts the link 118 in the position of Figure 9. When the levers 112 are worked to the left of Figure 9 the spring 121 will insure that the links 118 and 119 remain in their same relative position, whereby the locking tooth 117 is kept out of engagement with the locking notches of the various character wheels. A comb-like member having tines 119b is secured to the frame, and each tine is provided with a detent portion 119c to engage a locking notch of one of the character wheels. This arrangement permits movement of one wheel without disturbing the setting of the others. From the foregoing it will be observed that when the lever 112 is moved to the rear of the machine after the various printing wheels have been set up as desired (it being understood of course that the member 114 is retained in its solid line position so as to clear the tabs 110), the links 119 being secured to the hubs 120 will be pulled toward the left of Figure 5 and will in turn pull on the links 118 and the levers 115 so as to cause the locking tooth 117 to engage with the locking notches of the various printing wheels. When the levers 112 are pulled forward, the pivot point of the links 119 on the hubs 120 will be moved toward the right so that the locking tooth 117 is freed from engagement with the locking notches. In this condition then the various printing wheels can be set up as desired.

The hub 120 also carries a pin 125 which upon a forward stroke of the levers 112 abuts the extending end of the lever 63 to rock it in a clockwise direction against the tension of the spring 65 to raise the roller 61 off the gold leaf ribbon so that the ribbon can be advanced manually if desired.

Pencils which have been marked are discharged into a suitable hopper 130 at the end of the machine from whence they may be removed manually. Suitable switches to control electric circuits to the motor 23 and the heating element 108 may be provided on the front of the machine as at 131 and 132.

The purpose of the adjusting knob 39 mentioned heretofore which has the effect of moving the pivot point 34 up or down is to adjust the pressure with which the pencils are pressed against the printing wheels. Since the movement of the pivot point 33 cannot change, it will be clear that a change in the pivot point 34 will modify the stroke of the twisted link 45.

It will be clear that numerous modifications may be made without departing from the spirit of my invention. Thus I do not intend to be limited to specific details in construction and arrangement as shown in the drawings or described herein, other than as set forth in the claims which follow.

Having now fully described my invention, what

I claim as new and desire to secure by Letters Patent is:

1. A marking machine comprising a plurality of printing wheels coaxially mounted and which may be aligned to spell out a desired legend, each of said wheels being divided peripherally into three sections, one section carrying a series of printing characters, another section carrying a series of legible characters corresponding to said printing characters, and the third section carrying a series of locking notches equal in number to the number of said printing characters, an index bar parallel to the axis of said printing wheels and with respect to which said legible characters may be visually aligned whereby said printing characters are aligned to print the legend set up by means of the legible characters, a locking member having a portion to engage in the aligned locking notches of all said printing wheels to hold them in their set position during printing, and means for actuating said locking member, levers mounted adjacent each end of said plurality of printing wheels coaxially thereof, said levers being connected by a bar for manual actuation, said locking member being mounted on levers pivoted in said machine substantially in alignment with said first mentioned levers respectively, and a connection between the respective levers whereby actuation of said first mentioned levers by means of said manual bar in one direction will produce movement of said last mentioned levers to cause said locking member to engage in said locking notches.

2. A marking machine according to claim 1, wherein said connection comprises in each case a link pivotally connected to one of said first mentioned levers and also pivotally connected to one of said last mentioned levers, and spring means urging said levers in a direction to cause said locking member to clear said locking notches, except in the extreme locking position of said first mentioned levers.

3. A marking machine according to claim 2, in which each of said printing wheels is provided with a tab extending outward from its periphery by means of which it may be rotated, and wherein in said manual bar carries slidably and rockably thereon an abutment, which when rocked to one position engages a plurality of said tabs for zeroing said tabs.

4. A marking machine according to claim 3, 10 wherein said abutment is of a length to engage a limited number of said tabs at one time.

5. In combination with a marking machine having a bank of printing wheels having extending manually engageable tabs for positioning said 15 wheels, a pair of levers one at each end of said bank and mounted substantially coaxially with said wheels and connected at their outer ends by a bar, and an abutment rockably mounted on said bar, said abutment when rocked to one extreme 20 position extending inward of the ends of said tabs whereby upon rocking of said levers, bar and abutment, said tabs are returned to zero position.

6. The combination of claim 5, in which said 25 abutment is of a length to engage only a limited number of said tabs, and wherein said abutment is slidably mounted on said bar, whereby all said tabs may be zeroed by rocking said levers, bar and abutment a number of times with said abutment axially displaced for each stroke.

GREGORY G. WRIGHT.
